(57) **CLAIM**

The ornamental design for a roof box for vehicles, as shown and described.

DESCRIPTION

FIG. 1 is a front elevational view of the roof box for vehicles showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view taken from the front, top and right side of the roof box for vehicles; and,

FIG. 8 is a perspective view taken from the rear, top and left side of the roof box for vehicles.

In the drawings, the broken lines in FIG. 4 depict portions of the design that form no part of the claim.
